GRINDING GAUGE

James C. Fisk, G-3219 E. Bristol Road, Flint, Mich.

Filed Apr. 13, 1964, Ser. No. 79,473

Term of patent 14 years

(Cl. D52—6)

FIG. 1 is a side view of the grinding gauge showing my new design;

FIG. 2 is a front view of the grinding gauge of FIG. 1;
FIG. 3 is a rear view of the grinding gauge of FIG. 1;
FIG. 4 is a top view of the grinding gauge of FIG. 1;
FIG. 5 is a cross-sectional view taken at the line 5—5 of FIG. 1; and

FIG. 6 is a cross-sectional view taken on the line 6—6 of FIG. 1.

FIG. 7 is a fragmentary view of the side opposite to that shown in FIG. 1.

The essential features of my design are shown in full lines.

I claim:

The ornamental design for a grinding gauge, substantially as shown and described.
